UNITED STATES PATENT OFFICE

WILFRID V. N. POWELSON, OF NEW YORK, N. Y., AND WARREN TRAVELL, OF SAN BERNARDINO, CALIFORNIA

MOORING MAST FOR AIRSHIPS

Original application filed September 21, 1921, Serial No. 502,127. Divided and this application filed November 25, 1930. Serial No. 499,726.

This invention pertains to a mooring mast for airships. More particularly, it pertains to a mooring mast to which an airship may be easily moored regardless of the direction of the wind at the time of mooring or of the direction of approach of the airship. It also pertains to a mooring mast by means of which an airship may be moved under control between the level of the mast head and a level nearer the ground.

Masts are known which provide for the mooring of airships above the ground, but so far as we are aware the masts hitherto employed have not provided for the lowering or raising of the airship from one level to another under positive control. This has been a serious drawback because it has made difficult the handling of the ship, it being necessary, in order to bring a moored ship to the ground, to free it from the mast and pull it down in the usual way. Other disadvantages have been that it has been necessary to take on passengers and freight through the forward end of a moored ship, a procedure which is inconvenient, dangerous and slow, as well as disturbing to the equilibrium of the ship. Still another difficulty has been that mooring at the mast head has subjected the ship to stresses of greater magnitude than it would encounter if moored close to the ground.

It is an object of the present invention to eliminate those disadvantages by providing a structure to which an airship can be moored in the usual way, but by means of which the airship may be moved from one level to another, as, for example, from the mast head to a level nearer the ground, or vice versa. It will thus be possible to take on passengers and freight at a low level, as from a platform, to move the ship under positive control to the top of the mast, and then launch it by casting it loose from the mast.

We have invented various means for accomplishing these results, any one of which may be employed. Among them are mooring masts of the type specifically described in this application. Others involve the rotatable mounting of a mooring mast

equipped with a carriage moving vertically on tracks, a form of the invention described and claimed in our copending application filed September 21, 1921, Serial No. 502,127. Still a different solution of the problem is found in the use of a telescopic mooring mast provided at its end with a bell mouth or other means permitting rotation of the airship with respect to the mast.

The present application contains, among others, claims specific to a mooring mast equipped with a collar-like carriage on which a rotatable connecting device is mounted. By moving such collar-like carriage up or down, the elevation of the moored airship is changed at will. By means of the rotatable ring which forms a part of the carriage, rotation of the moored airship around the mooring mast is permitted.

In the accompanying drawings, forming a part hereof:

Figure 1 is a diagrammatic elevation of a mooring mast with a sliding collar-like carriage;

Figure 2 is a cross-section on line 2—2 of Figure 1, on a larger scale;

Figure 3 is a cross-section on line 3—3 of Figure 2;

Figure 4 is plan of the base of the mast; showing the platform which forms a part thereof;

Figure 5 is a plan on a larger scale of the mechanism for controlling movement of the sliding collar and mooring connection; and

Figure 6 is an elevation corresponding to Figure 5.

In Figure 1 is shown a preferred type of self-sustaining mooring mast, the same comprising a tower and a platform and being designated 330. Attached thereto is the airship 1, held to the mast 330 by rope 80. This mast 330 is movable on track 331 and has a collar-like carriage 332 which is capable of sliding motion up and down said mast, such motion being controlled by ropes 333 leading to a hoisting machine 334. As shown in Figures 5 and 6, the hoisting machine 334, which may be of any well known or suitable type, has a drum 370 driven

through a gearing 371 by an electric motor 372.

A similar hoisting machine 335 is used for controlling the rope 80 which attaches the air ship to the mast and forms a flexible connection thereto. This rope 80 passes around a sheave 360 which is carried by a ring 361 revolvable around the collar-like carriage 332. If desired, anti-friction rollers 362 may be used between said ring and said collar-like carriage 332. The rope 80 after passing around the sheave 360 is led upward around a sheave 336 carried by a caster 337 revolvable about the central axis 15 of the mast and having an opening through its center through which rope 80 may be led downward to its control means 335.

Figures 2 and 3 show in greater detail a method of constructing a mast with an inner cylinder 351 concentric with the outer cylinder 332 and having web-girders 353 between. Any other suitable method may be used for obtaining a mast of sufficient strength and rigidity to withstand the stresses imposed upon it by the airship.

By this arrangement, it is possible to moor the airship 1 to the mast 330 in the usual way, and, having moored it, to lower it from the mooring level to any desired lower level. This slidable carriage 332 provides for such vertical movement and the connecting rings 362, forming a part of the carriage, provides for rotation of the airship in response to changes in the direction of the wind.

Suitable changes to adapt the mast to particular conditions may be made without departing from the inventive thought.

The subject matter of this application constitutes divisional matter taken from our copending application Serial No. 502,127, filed September 21, 1921, for "Means for mooring and housing airships." It is intended that the patent to be based on the present application shall cover, by suitable expression in the appended claims, whatever features of patentable novelty reside in the invention herein disclosed, within the scope above indicated.

We claim:

1. In equipment for mooring airships, the combination of a mooring tower; a rotatable mooring element cooperating with the exterior surface of the tower, said element having means which is flexible, as regards its vertical angle of elevation, for its connection to the ship; and mechanical means by which said rotatable mooring element may be raised and lowered under control.

2. A self supporting mooring mast for airships comprising a tower, a connecting device associated with said tower with which the airship is connected, said connecting device adapted to be moved longitudinally along the tower while the airship is con-

nected thereto and to be moved circumferentially about said tower.

3. A mooring device for airships comprising an anchor structure; rotatable means for connecting an airship to said structure when approaching from any direction; and means for changing the direction in which said anchor structure lies so as to correspond with the position of the ship, said means comprising wheels connected with the anchor structure.

4. A mooring device for airships comprising a platform, a tower associated therewith, a sliding collar for the airship connected with said tower and adapted to slide vertically along it.

5. Apparatus for mooring airships comprising a mooring mast, a carriage having vertical movement along said mast, said carriage being provided with means rotatable thereabout and provided with a device to which the airship is adapted to be moored.

6. A method of mooring airships comprising the securing of the ship by the bow to an elevated coupling, maintaining said coupling in condition to revolve freely about a fixedly positioned tower as the ship moves with the wind, and lowering the coupling to a predetermined elevation.

7. A mooring mast comprising an internally trussed structure, a vertically movable member secured to rotate around the outside of the mast, a mooring line coupling cooperating with said member, and means to control vertical movement thereof.

8. In equipment for mooring airships, the combination of a mooring tower; a rotatable mooring element cooperating with the exterior surface of the tower; and mechanical means by which said rotatable mooring element may be raised and lowered under control.

9. A self supporting mooring mast for airships comprising a tower, a rotatable connecting device associated with said tower with which the airship may be connected, said connecting device adapted to be moved longitudinally along the tower while the airship is connected thereto.

Signed at San Bernardino, California, this eleventh day of November, 1930.

WILFRID V. N. POWELSON.
WARREN TRAVELL.
